2,157,390

METHOD FOR MAKING CAST IRON

William J. Priestley, New Rochelle, N. Y., assignor to Electro Metallurgical Company, a corporation of West Virginia

No Drawing. Application January 25, 1937,
Serial No. 122,235

9 Claims. (Cl. 75—58)

The invention relates to cast iron and provides a novel method and means for improving cast irons of all varieties. The invention will be described in connection with gray cast iron made in the cupola with little or no steel in the charge; but the invention is equally suitable for use to improve all varieties of cast iron, including white and mottled iron and irons of mixed or graded structures, when made in any type of furnace from any kind of charge.

Sources of weakness in gray cast iron are the formation of large graphite flakes and large grains in heavy sections, too deep a chill in light sections, and too large an amount of "eutectic" graphite in sections behind a chill. An ideal gray cast iron would have a uniform fine-grained structure, uniform chill characteristics, and fine flake graphite uniformly distributed.

It is well known that the chilling characteristics of a cast iron may sometimes be reduced by a relatively small addition of graphite in the forehearth or ladle. This effect is accompanied, however, by a softening of the metal and, in some cases, by a decrease in its tensile and transverse strengths. These effects are illustrated by the data in Table A.

Table A

No.	Ladle addition	Analysis of cast iron			Tensile strength, lb/sq. in.	Transverse strength, lb/sq. in.	Deflection, inches	Brinell hardness number
		T. C. percent	Percent Si	Percent Mn				
1	None	2.95	2.98	0.6	31,160	3,620	0.18	170
2	Graphite*	3.05	2.85	0.6	30,425	3,100	0.15	166

* 4 ounces of graphite per 100 pounds of metal.

It is also known that the chilling characteristics can be reduced by adding silicon or zirconium, in small amounts, in cupola, forehearth, or ladle. In order to secure markedly improved results by this means, however, it is necessary to use so much of the silicon addition that the composition is changed substantially, and the base mixture must be altered to compensate for this change so that the correct final composition will be obtained. Sometimes, the chill in light sections of a casting cannot be suppressed by this expedient without producing undesirably coarse graphite in the heavier section.

On occasion, both ferrosilicon (containing 50% silicon) and graphite have been added to cast iron, almost simultaneously but not in admixture. As would be expected, the effects of the two ma-

terials are substantially additive when they are added in this fashion.

I have discovered that if graphite, or other form of carbon, is intimately mixed with silicon or zirconium, or both, and this intimate mixture is added in relatively small amount to a molten cast iron, the iron is improved to an extent, and in a manner, quite different from what could be predicted from the previous knowledge of the individual effects of the constituents of the mixture.

Specifically, such a mixture refines the grain and the graphite flakes in heavy sections, reduces or eliminates chill, suppresses or inhibits the formation of eutectic graphite, inhibits the formation of an open grain structure inside heavy sections, and raises the tensile and transverse strength without greatly altering the ductility or hardness of the main body of the casting, the effects obtained depending, of course, on the composition of the melt and the casting conditions.

Although graphite is preferred as the carbonaceous ingredient of the mixture, because of its ready solubility in molten iron, other forms of carbon, such as charcoal, coal coke, petroleum

coke, or carbon black, may be used. The silicon or zirconium may be used in any of the commercial forms of these elements, such as silicon metal, ferrosilicon, or silicon-zirconium alloy. When ferrosilicon is used, it is particularly advantageous to use a ferrosilicon containing at least 65% silicon. Ferrosilicon having a lower proportion of silicon appears to cool the iron at least locally, while those having at least 65% silicon generate enough heat by exothermic reaction to counteract any cooling effect.

A mixture of approximately equal parts by weight of graphite and 85% grade ferrosilicon will be found to be of most general suitability, although mixtures containing other proportions may be used. If a relatively large amount of the mixture is employed, the proportions may range from 5% carbon and 95% ferrosilicon or its

equivalent, to 95% carbon and 5% ferrosilicon or its equivalent; but if only a small amount of mixture is used, the proportions should be between 25% and 75% carbon, remainder ferrosilicon or its equivalent.

The ingredients of the mixture should be finely subdivided and intimately mixed. Particle sizes from that just passing a three mesh screen to fine powder have been used successfully, and somewhat larger particles are useful. The mixture may be used as loose grains or powder.

The amount of mixture to be added will vary, of course, with the type of cast iron and the intensity of the effect desired; but in no case need it be sufficient to alter substantially the chemical composition of the cast iron. Additions of 4 to 8 ounces of the mixture for each 100 pounds of cast iron have given excellent results; but smaller or larger amounts, between the approximate limits of 1 to 16 ounces per 100 pounds of cast iron, are useful, the upper limit being set chiefly by considerations of economy and change of composition.

The benefits conferred by the invention are illustrated by the data appearing in Table B:

Table B

No.	Ladle addition	Analysis of cast iron			Tensile strength, lb/sq. in.	Transverse strength, lb/sq. in.	Deflection, inches	Brinell hardness number
		Percent Si	T. C. percent	Percent Mn				
3	None	1.58	2.95	0.6	32,785	3,390	0.09	220
4	*	1.56	3.05	0.6	38,080	3,730	0.10	239
5	**	1.62	2.90	0.6	40,400	3,750	0.11	228
35	None	1.84	3.16	0.7	37,180	2,340	0.22	-----
6	**	1.95	3.20	0.7	40,160	2,800	0.30	-----
7	None	1.95	3.18	0.8	-----	2,220	0.19	-----
8	*	1.98	3.24	0.8	-----	2,760	0.28	-----
9	None	2.98	2.95	0.6	31,160	3,620	0.18	170
10	*	2.98	2.95	0.6	40,500	3,740	0.13	223

* 4 ounces of addition mixture per 100 pounds of cast iron.
** 8 ounces of addition mixture per 100 pounds of cast iron.

Addition mixture consisted of equal parts by weight of graphite and ferrosilicon containing 85% Si.

In Tables A and B, the symbol "T. C." means total carbon; and tensile strength and transverse tests were made in accordance with the standard A. S. T. M. specifications. The transverse tests on samples 6, 7, 8, and 9 were made on supports 18 inches apart; on the remaining samples, on supports 12 inches apart.

The presence of large amounts of strong carbide-forming elements, in the cast iron, such as more than 10% of chromium, masks or destroys the beneficial effects of the invention by preventing graphitization of the combined carbon.

The chill ordinarily produced in low-silicon irons by the presence of a high sulfur content is reduced or eliminated by the use of the addition mixture of the invention. For instance, a melt of white-iron composition containing 0.75% silicon, 0.28% manganese, 0.31% sulfur, 0.143% phosphorus, 2.86% carbon, remainder iron, was treated by the addition of a small amount of the addition mixture referred to in Table B, and the melt cast. The casting was found to be a mottled iron instead of a white iron.

Modifications of the invention as described herein will readily occur to those skilled in the art. Accordingly, the invention is not limited to the specific examples mentioned above by way of example.

I claim:

1. Method of increasing the strength of cast iron which comprises adding to a molten cast iron an unbonded intimate mixture containing 25% to 75% carbon and at least one element

selected from the group consisting of silicon and zirconium, the amount of said mixture added being between one and sixteen ounces for each 100 pounds of molten cast iron; and casting the melt.

2. Method of making cast iron which comprises adding to a molten cast iron an effective amount of an unbonded intimate mixture containing 25% to 75% graphite and the remainder principally ferrosilicon containing at least 65% silicon, the amount of said mixture added being insufficient to change substantially the chemical composition of said molten iron, and casting the melt.

3. Method of making cast iron which comprises adding to a molten cast iron an effective amount of an unbonded intimate mixture consisting essentially of graphite and ferrosilicon in substantially equal amounts by weight, the ferrosilicon containing at least 85% silicon, the amount of said mixture added being insufficient to change substantially the chemical composition of said molten iron, and casting the melt.

4. The method of reducing the chill of a high-sulfur, low-silicon cast iron containing not less

least 65% silicon; the proportions of graphite and ferrosilicon in said mixture being approximately equal by weight, and the amount of said mixture added being insufficient to change substantially the chemical composition of said molten iron; and casting the melt.

8. An agent for treating molten cast-iron in a forehearth or ladle, consisting of an unbonded intimate admixture of powdered materials and composed wholly of carbon and material selected

from the group: silicon, ferrosilicon, zirconium, and silicon-zirconium; the carbon being between 25% and 75% of the agent.

9. An agent for treating molten cast-iron in a forehearth or ladle, consisting entirely of an unbonded intimate admixture of powdered graphite and powdered ferrosilicon in approximately equal parts by weight.

WILLIAM J. PRIESTLEY. 10
